LOUVRED WALL OR SIMILAR ARTICLE

Fred Jacobs, 59 Netto Lane, Plainview, N.Y.

Filed May 7, 1962, Ser. No. 69,995

Term of patent 14 years

(Cl. D62—4)

Fig. 1

Fig. 2

FIG. 1 is a front perspective view of a louvred wall or similar article, showing my new design; and

FIG. 2 is a sectional view thereof, taken on the line 2—2 of FIG. 1.

The rear view is reverse in appearance from the front as indicated by FIG. 2.

I claim:

The ornamental design for a louvred wall or similar article, substantially as shown and described.
